UNITED STATES PATENT OFFICE.

ARTHUR W. WARNER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

MEANS FOR PREVENTING THE ESCAPE OF DUST, &c.

1,137,558.

Specification of Letters Patent. Patented Apr. 27, 1915.

Application filed February 15, 1913. Serial No. 748,641.

To all whom it may concern:

Be it known that I, ARTHUR W. WARNER, citizen of the United States, residing at Sewickley, in the county of Allegheny and State of Pennsylvania, have invented certain new and useful Improvements in Means for Preventing the Escape of Dust, &c., of which the following is a specification.

A prime object of my invention is to provide means for preventing the escape of dust and other fine particles, during the operation of discharging coal, ore, etc., from a storage bin to a hopper.

The present invention is particularly applicable for use in connection with charging apparatus employed in a gas retort house for charging coal into retorts, and in the embodiments as illustrated in the drawing, I have shown a stationary bin and the upper portion of a coal hopper, the latter being carried on a charging machine designed to travel in front of a bench of retorts and under the stationary storage bin.

In the accompanying drawing illustrating an application of my invention: Figure 1 is a vertical sectional view of a portion of a coal bin and a portion of the upper end of a coal hopper designed to be carried on the charging apparatus; Fig. 2 is a detailed plan and sectional view, the section being taken on line II-II of Fig. 1; Fig. 3 is an enlarged side elevational view particularly showing a guide rod and adjusting nuts; and Fig. 4 is a part horizontal sectional view and a part plan, the section being taken on line IV-IV of Fig. 3 looking in the direction of the arrows.

Referring to the drawing, 1 designates a stationary bin having a sloping bottom and coal discharging openings 2, the latter being controlled by doors or gates 3 operatively connected with an operating rod 4, said rod being designed to be moved to open the door by any suitable means, not shown. The stationary bin, as illustrated, is of rectangular shape, and is provided with depending side members 5, a depending rear member 6, and a depending front member, not shown, corresponding with the said side and rear depending members. The said members, when assembled and secured to the bin, constitute

a rigid rectangular frame. Secured to the lower edges of the said side, front and rear depending members, I provide strips or pieces 7 of some suitable flexible material as strong canvas, the upper edges of said strips being held between the downwardly depending members and bars 8, the latter being secured to the rigid frame by means of bolts 9 passed through the bars 8 and the upper lapped-over edges of the flexible piece or pieces 7.

10 designates metallic members adapted to be secured to the respective side members 5 by bolts 11. Members 10 are similar to the bracket members 21 (see Fig. 4) and are provided with sleeves 12 preferably formed integral therewith into which guide rods 13 are entered. For the purpose of giving a slight play to the guide rods, the interior of the sleeves 12 are preferably beveled as particularly shown at 14 in Fig. 3. Guide rods 13 are designed to be moved vertically through the sleeves 12, and the upper ends of said rods are screw threaded and provided with adjusting nuts 15 and 16.

17 designates a rigid metallic frame of rectangular shape comprising inner bars 18 and an outer flanged member or members 19. This frame is attached to the lower edges 80 of the flexible strips or pieces 7 by having the overlapped edges thereof entered between the inner and outer members 18 and 19, which members are secured together by a series of bolts 20.

Bolted or otherwise secured to the lower frame just described, and in line with the respective sleeves 12 of members 10, I provide bracket members 21 each formed with an internally threaded collar portion 22 into which the lower ends of the respective guide rods are adapted to be screwed. As particularly shown by Fig. 3, the lower ends of the guide rods 13, in addition to being threaded, are each provided with a bolt opening 23, which opening registers with a horizontally extending bolt opening 24 in the sleeve, and 25 designates a bolt passed through the sleeve, guide rod, and the lower rigid frame. The means just described constitute simple and efficient closure means depending from the storage bin and adapted to coöperate

with the hopper or other receptacle into which the material contained in the bin is to be introduced.

The coal hopper or other receptacle designed to receive coal or other material from the discharge opening of the stationary bin is indicated by 26, and as above stated, this hopper 26 is designed to be carried on the upper portion of a charging apparatus not shown. The hopper or the opening through which the material is introduced to the hopper is of rectangular shape and is bounded by a mouth-piece 27. This mouth-piece 27 is designed to make contact with the closure means or the lower metallic frame thereof, as the charging apparatus carrying the hopper is moved under the bin.

As will be seen, the flanged portions 19 and the mouth-piece 27 are complementally formed so as to provide for an automatic raising of the frame 17 by the positioning of the hopper below the discharge openings, the nuts 15 and 16 being adjusted so as to cause said frame to have its lower position at a point where the coacting faces of these flanged portions will provide a proper meeting without damaging either frame or hopper, the movement of the hopper to position moving the frame vertically, the rods 13 moving upwardly, as shown in Fig. 1, and thus causing said frame 17 to act somewhat as a floating frame. When the hopper passes out of engagement with the frame, the latter returns to its lower position, the nuts 15 acting to limit the length of such return movement.

From the construction described, it will be noted that I have provided simple and efficient means for preventing the escape of dust, etc., into the building in which the apparatus is located during the operation of transferring the coal, etc., from the stationary bin to the movable hopper.

What I claim is:

1. In combination, a bin having a discharge opening, a hopper positionable below said opening, and means carried by the bin for closing the space between the bin and hopper against escape of dust, etc., said means including a frame movable vertically in one direction by the positioning of the hopper below the opening.

2. In combination, a bin having a discharge opening, a hopper positionable below said opening, and means carried by the bin for closing the space between the bin and hopper against escape of dust, etc., said means including a frame movable vertically in one direction by the positioning of the hopper below the opening, said discharge opening being positioned permanently above the top plane of the hopper.

3. In combination, a bin having a discharge opening, a hopper positionable below said opening, and means carried by the bin

for closing the space between the bin and hopper against escape of dust, etc., said means including a frame movable vertically in one direction by the positioning of the hopper below the opening, said means extending permanently below the plane of the discharge opening.

4. In combination, a bin having a discharge opening, a hopper positionable below said opening, and means carried by the bin for closing the space between the bin and hopper against escape of dust, etc., said means including a frame movable vertically in one direction by the positioning of the hopper below the opening, said frame and hopper being complementally formed to cause automatic raising of the frame by the hopper.

5. In combination, a bin having a discharge opening, and a dust-retaining structure external of the opening, said structure being rendered active by the positioning of a hopper below the opening and including a frame permanently positioned below the plane of the opening and movable vertically to accommodate for the positioning of the hopper.

6. In combination, a bin having a discharge opening, and a dust-retaining structure external of the opening, said structure being rendered active by the positioning of a hopper below the opening and including a frame permanently positioned below the plane of the opening and movable vertically to accommodate for the positioning of the hopper, and means carried by the frame and co-operating with the bin for guiding the frame in its vertical movement and for limiting the return movement of the frame.

7. In combination, a bin having a discharge opening, and a dust-retaining structure external of the opening, said structure being rendered active by the positioning of a hopper below the opening and including a frame permanently positioned below the plane of the opening and movable vertically to accommodate for the positioning of the hopper, and means carried by the frame and co-operating with the bin for guiding the frame in its vertical movement and for limiting the return movement of the frame.

8. In combination, a bin having a discharge opening, and a dust-retaining structure external of the opening, said structure being rendered active by the positioning of a hopper below the opening and including a frame permanently positioned below the plane of the opening and movable vertically to accommodate for the positioning of the hopper, and means carried by the frame and co-operating with the bin for guiding the frame in its vertical movement and for

limiting the return movement of the frame, said means including adjustable members for controlling the length of such return movement, said stop members acting to support the frame in its lower position.

9. In combination, a bin having a discharge opening, a depending frame carried by the bin external of said opening, a vertically movable frame below said fixed frame and connected thereto by a flexible apron, and guide members connecting said frames external of the apron, said members forming the support for said vertically movable frame in its lower position.

10. In combination, a bin having a discharge opening, a depending frame carried by the bin external of said opening, a vertically movable frame below said fixed frame and connected thereto by a flexible apron, and guide members connecting said frames external of the apron, said members forming the support for said vertically movable frame in its lower position and being in the form of rods having their upper ends movable with respect to the fixed frame, such upper ends and the fixed frame

having complemental means for adjusting the lower position of said movable frame.

11. In combination, a bin having a discharge opening, a depending frame carried by the bin external of said opening, a vertically movable frame below said fixed frame and connected thereto by a flexible apron, and guide members connecting said frames external of the apron, said members forming the support for said vertically movable frame in its lower position and being in the form of rods having their upper ends movable with respect to the fixed frame, such upper ends and the fixed frame having complemental means for adjusting the lower position of said movable frame, said movable frame having its lower face in the form of an outwardly projecting flange forming a seating face adapted to cooperate with a similar face on the hopper.

In testimony whereof I affix my signature in presence of two witnesses.

ARTHUR W. WARNER. [L.S.]
